UNITED STATES PATENT OFFICE.

SOREN THURSTENSEN, OF LOUISVILLE, KENTUCKY, ASSIGNOR TO HENRY VOGT
MACHINE COMPANY, OF LOUISVILLE, KENTUCKY, A CORPORATION OF KENTUCKY.

FURNACE-GRAVE.

1,292,923.

Specification of Letters Patent. Patented Jan. 28, 1919.

Application filed July 31, 1916. Serial No. 112,304.

To all whom it may concern:

Be it known that I, SOREN THURSTENSEN, a citizen of the United States, residing at Louisville, in the county of Jefferson and 5 State of Kentucky, have invented certain new and useful Improvements in Furnace-Grates, of which the following is a specification.

In the construction of familiar types of 10 furnace grates, there are provided grate sections which are oscillatably mounted in suitable bearings, so that they can be rocked about horizontal axes. In the ordinary operation of shaking down the grate, these 15 sections are oscillated back and forth substantially equal amounts on both sides of the central or normal position. When it is desired to dump the grate, the grate sections are rocked an additional amount in 20 the dumping direction, so that their upper or grate surfaces are thrown into substantially vertical positions. The various grate sections are mounted in suitable bearings, which bearings in turn are formed in horizontal bars lying at right angles to the direction 25 of the grate bar sections. Ordinarily the grate bar sections extend across the furnace and the bearing bars extend from front to rear. It is customary to provide one of 30 these bearing bars at each side of the furnace. When the furnace is so wide as to make it undesirable to use grate bars of full width, the furnace is divided up into two or more sections. Each of these sections is 35 of less width than the width of the furnace, and supporting bars are mounted between the adjacent edges of consecutive sections. These supporting bars provide bearings for the inner ends of the adjacent grate 40 bars.

In all previous constructions of grate with which I am familiar no attempt has been made to carry the grate bars over the bearings of the supporting bars, so that the said 45 bearings have been exposed to the intense heat of the fuel bed. Furthermore this omission in previous forms of construction has resulted in the provision of an uneven grate surface, there being depressions or 50 openings in the surface of the grate at the

points where the bearings are located. Coal and ashes necessarily accumulate in these openings, and this tends to jam the bars so that they cannot be readily rocked.

One of the objects of the present invention is to provide a construction of grate in which the said bearings will at all times be covered over and protected by grate sections, so that when the grate bars are standing in their central or normal position there 55 will be presented a practically continuous grate surface throughout the entire area of the furnace. This will prevent the coal and ashes from having direct communication with the bearings, and at the same time will 60 largely overcome the aforementioned difficulty and objection, due to the jamming of the grate bars when they are being oscillated.

Another feature of the invention has to do with the manner in which the grate bars 70 are built up. In this connection one object is to provide a sectional grate bar which can be built up from a minimum number of parts to the desired size, all of the parts being of standard form and construction. 75

Other objects and uses of the invention will appear from a detailed description of the same which consists in the features of construction and combinations of parts hereinafter described and claimed. 80

Referring to the drawings:

Figure 1 shows a plan view of a grate embodying the features of the present invention, said grate comprising two sections lying side by side with an intermediate bearing bar, the central portion of one of the sections being broken away for the purpose of reducing the width of the figure; 85

Fig. 2 shows a longitudinal section taken on the line 2—2 of Fig. 1, looking in the 90 direction of the arrows;

Fig. 3 shows a side elevation of one of the rocking bars with the grate sections in place, the upper portions of the grate sections being broken away for the purposes 95 of convenience and illustration;

Fig. 4 shows a plan view corresponding to Fig. 3, with the exception that the grate sections have been removed in their entirety;

Fig. 5 shows a cross section taken on the 100

line 5—5 of Fig. 1, looking in the direction of the arrows, Fig. 5 being on a smaller scale than Fig. 1;

Fig. 6 shows a cross section taken on the line 6—6 of Fig. 3, looking in the direction of the arrows;

Fig. 7 shows a horizontal section taken on the line 7—7 of Fig. 6, looking in the direction of the arrows;

10 Fig. 8 shows an enlarged side elevation of one of the cap sections as the same is mounted on the central bearing bar; and

Fig. 9 shows a horizontal section taken on the line 9—9 of Fig. 8, looking in the direction of the arrows.

In the several figures, the side walls of the furnace are designated by the numerals 10 and 11. The furnace door is designated by the numeral 12 and the bridge wall by the 20 numeral 13. In the construction illustrated the furnace is of such width that two grate sections are used, the same being mounted side by side and being designated by the numerals 14 and 15. Each of these sections 25 runs the full depth of the furnace, although manifestly, if desired, each grate section might be constructed to occupy only a portion of the depth of the furnace, the number of sections being multiplied accordingly.

30 In like manner a greater or lesser number of sections may be used across the width of the furnace according to the requirements of the particular construction in hand.

Each grate section is built up from one or 35 more bars 16 on which are mounted the leaves 17. The end portions of each bar 16 are suitably journaled. In the construction illustrated, this journal is effected by means of the side bars 18 and 19, and the center 40 bar 20, the center bar serving to support the inner ends of all of the grate bars. Each grate bar is provided with a downwardly depending lug 21, and all of the grate bars of each section are joined together by a 45 rocking bar 22 which can be swung back and forth by means of a handle 23 in the usual manner.

Each grate bar 16 is preferably formed of greater depth than its width, and its central 50 portion may be cut away to provide an elongated slot or opening 23^a. This will lighten the bar without materially detracting from its mechanical strength. The side portions of each grate bar are provided with 55 the vertical slots or grooves 24 formed in pairs on opposite sides of the bar. These pairs of slots or grooves accommodate the arms 25 and 26 of the leaves in the manner indicated in Figs. 3, 4, 6 and 7. When all 60 of the leaves have been set in position on a grate bar, they may be locked in such position by means of a rod 27. This rod extends between grooves 28 formed in the leaves, and grooves 29 formed in the side portion

of the grate bar. Manifestly it is impossible 65 to remove any leaf without first withdrawing the rod 27.

The upper portions of the leaves are of greater width than their depending lug portions 25 and 26, and said upper portions are 70 serrated as particularly shown in Fig. 1.

Upon oscillating any given grate bar, all of its leaves will be swung back and forth, while the end portions of the grate bar oscillate within the bearings of the center and 75 side bars.

An examination of Fig. 1 in particular shows that the space occupied by the center bar 20 is substantially equal to that occupied by a row of leaves extending from 80 front to rear of the furnace, and such examination will also show that the furnace width occupied by each of the side bars 18 and 19 is substantially equal to one-half the width of a row of leaves. Consequently unless 85 some means is provided for protecting the center and side bearing bars, a very considerable portion of the furnace area will be left unoccupied by any of the grate leaves. In order to remedy this deficiency, I have 90 provided the constructions which I will now describe.

Reference particularly to Figs. 2, 5, and 8 will disclose the fact that the bearings are formed in the bearing bars by the provision 95 of upstanding lugs or the like 30 and 31 which are formed in pairs on the upper portions of the various bearing bars. The end portions 32 and 33 of the grate bars are rounded and rest within the U-shaped bearings thus provided. A stationary cap section 34 is seated over each of the bearings and serves not only to cover over and close the same, but also serves to restore the continuity of the upper surface of the grate 105 when all the bars stand in their central positions. Each of the stationary leaves is provided with downwardly depending side lugs 35 and 36 which embrace between them the upstanding lugs 30 and 31 of the bearing 110 bar. It will be observed particularly from an examination of Fig. 8 that the side faces of the lugs 30 and 31 both slant in one direction, the lugs 35 and 36 being similarly 115 formed. A key 37 may be driven home between a keyway 38 formed in the lug 31 and a notch 39 formed in the lug 36. When the said key is driven home, it will be impossible for the lug 36 to rise along the lug 31, and by reason of the outward pitch of the lug 30 120 it will be impossible for the lug 35 to rise across the face of the lug 30 until the key 37 has been withdrawn.

Those stationary leaves which are mounted on the center bearing bar are of a contour 125 similar to the contours of the leaves mounted on the grate bars—that is, they are serrated on both of their side faces. On the other

hand the stationary leaves mounted on the side bearing bars are of lesser width, and are serrated on only their inner faces, their unserrated faces lying in contact with the side walls of the furnace.

While I have herein shown and described only a single construction of furnace grate embodying the features of my invention, still it will be understood that I do not limit myself to the said construction except as I may do so in the claims.

I claim:

1. In a furnace, the combination of spaced bearing bars arranged in parallel relation and having on their upper portions upwardly extending pairs of spaced lugs affording journal bearings, rocking grate bars having end journals resting in said bearings and having grate surfaces on their upper portions, and cap sections on the journal bearings inclosing their upper portions, each cap section having a pair of depending side lugs adapted to embrace the side lugs of the corresponding journal bearing, the 25 coacting faces of each set of engaging lugs on both sides of the bearing being all pitched in substantially the same oblique direction, whereby the backward pitch of the lug on one side of the journal bearing will 30 interlock with the coacting lug of the corresponding cap section, and a key interengaging the opposite pair of lugs for maintaining the interlock, substantially as described.

2. In a furnace, the combination of spaced bearing bars arranged in parallel relation and having on their upper portions upwardly extending pairs of spaced lugs affording journal bearings, rocking grate bars having end journals resting in said bearings 40 and having grate surfaces on their upper portions, and cap sections on the journal bearings inclosing their upper portions, each cap section having a pair of depending side lugs adapted to embrace the side lugs of the corresponding journal bearing, the coacting faces of each set of engaging lugs on both sides of the bearing being all pitched in substantially the same oblique direction, whereby the backward pitch of the lug on 45 one side of the journal bearing will interlock with the coacting lug of the corresponding cap section, and a key interengaging the opposite pair of lugs for maintaining the interlock, each cap section having 50 its upper surface of contour similar to the contour of the grate surfaces of the adjacent rocking sections and continuous therewith when the rocking sections stand in their normal position, substantially as described.

3. In a furnace, the combination of spaced bearing bars arranged in parallel relation

and having on their upper portions upwardly extending pairs of spaced lugs affording journal bearings, rocking grate bars having end journals resting in said bearings, a series of grate leaves for each grate bar, having grate surfaces on their upper faces and having arms embracing the sides of the bar, a locking rod for each grate bar jointly engaging portions of the arms and the portions of the grate bar for locking the leaves to the grate bars, and cap sections on the journal bearings inclosing their upper portions, each cap section having a pair of depending side lugs adapted to embrace the side lugs of the corresponding journal bearing, the coacting faces of each set of engaging lugs on both sides of the bearing being all pitched in substantially the same oblique direction, whereby the backward pitch of the lug on one side of the journal bearing will interlock with the coacting lug of the corresponding cap section, and a key interengaging the opposite pair of lugs for maintaining the interlock, substantially as described.

4. In a furnace, the combination of spaced bearing bars arranged in parallel relation and having on their upper portions upwardly extending pairs of spaced lugs affording journal bearings, rocking grate bars having end journals resting in said bearings, a series of grate leaves for each grate bar, having grate surfaces on their upper faces and having arms embracing the sides of the bar, a locking rod for each grate bar jointly engaging portions of the arms and portions of the grate bar for locking the leaves to the grate bars, and cap sections on the journal bearings inclosing their upper portions, each cap section having a pair of depending side lugs adapted to embrace the side lugs of the corresponding journal bearing, the coacting faces of each set of engaging lugs on both sides of the bearing being all pitched in substantially the same oblique direction, whereby the backward pitch of the lug on one side of the journal bearing will interlock with the coacting lug of the corresponding cap section, and a key interengaging the opposite pair of lugs for maintaining the interlock, each cap section having its upper surface of contour similar to the contour of the grate surfaces of the adjacent locking sections and continuous therewith when the locking sections stand in their normal position, substantially as described.
